UNITED STATES PATENT OFFICE.

GEORGE A. GUNTHER, OF NEW Utrecht, NEW YORK.

SNOW-PLOW.

SPECIFICATION forming part of Letters Patent No. 281,496, dated July 17, 1883.

Application filed January 27, 1883. (No model.)

To all whom it may concern:

Be it known that I, GEORGE A. GUNTHER, of New Utrecht, in the county of Kings and State of New York, have invented a new and Improved Snow-Plow, of which the following is a full, clear, and exact description.

The object of my invention is to provide a new and improved snow-plow provided with devices for scattering and loosening the snow 10 and facilitating the entrance of the plow into the snow.

The invention consists in the combination, with a snow-plow, of a tube for ejecting torpedoes to be exploded in front of the plow.

15 The invention further consists in an anvil or other obstruction held in front of the end of the tube, against which anyil the torpedoes strike and are exploded, all as will be fully set forth hereinafter.

20 Reference is to be had to the accompanying drawing, forming a part of this specification, in which a longitudinal elevation of a locomotive-engine provided with my improved snow-plow is shown, parts being in section.

25 A tube, A, made about in the same manner as a gun-barrel, projects about eight feet from the front of a snow-plow, B, made of thick iron plates, and held in front of the locomotive-engine C. From the front end of the 30 tube A an arm, D, projects about two feet, to the outer end of which arm a block or anvil, E, or other obstruction is fastened in such a manner that torpedoes ejected from the end of the tube A must strike against it and will 35 be exploded. The end of the tube A is suitably braced and supported. The tube A extends from the snow-plow to the caboose F, and is connected with a compressed-air reservoir, G, (shown in dotted lines,) or to an

40 air-pump. Means are to be provided for keeping the reservoir filled with compressed air. A suitable receptacle, H, for torpedoes is provided, from which they can be successively passed into the tube A. Neither the 45 torpedo-receptacle nor the reservoir for the compressed air need necessarily be located in the caboose, but can be located in any other suitable part of the locomotive. The torpedoes are to be made of such material that 50 they will only be exploded when forcibly thrown against a solid object, and will not be exploded by the shocks received by the jolting of the locomotive.

The operation is as follows: The plow is 55 forced into the snow, and then a torpedo is

conducted into the tube A and ejected from the end of the same and thrown forcibly against the anvil E by means of compressed air admitted into the tube A from the reservoir G. The torpedo explodes and scatters and loosens the snow in front of the plow, thus facilitating the entrance of the plow into the snow. The above operation is repeated every few seconds, or as often as may be necessary.

Instead of firing the torpedo by means of compressed air, a vacuum may be created in the tube and the torpedo fired out of the tube by the air suddenly admitted into the tube. In place of compressed air, steam of sufficient pressure may be used.

If desired, a number of tubes or barrels, A, may be combined with a plow, and a number of torpedoes fired simultaneously. The torpedoes may also be of such nature that when fired into the snow from the barrel or tube 75 they will explode of their own account, and without striking against the anvil E or other obstruction.

If desired, the end of the tube can be bent or curved to throw the torpedoes against the 80 plow and explode them.

Having thus described my invention, what I claim as new, and desire to secure by Letters Patent, is—

1. The combination, with a snow-plow, of 85 a tube or barrel for ejecting torpedoes, substantially as herein shown and described, and for the purpose set forth.

2. The combination, with a snow-plow, of 90 a tube or barrel for ejecting torpedoes, and of an obstruction held in front of the end of the tube, substantially as herein shown and described, and for the purpose set forth.

3. The combination, with a snow-plow, of 95 a tube or barrel for ejecting torpedoes, projecting some distance from the front of the snow-plow, and of an obstruction held in front of the end of the barrel or tube, substantially as herein shown and described, and for the purpose set forth.

4. The combination, with a snow-plow, of 100 the tube or barrel A, for ejecting torpedoes, the arm D, projecting from the end of the tube, and of the anvil E on the end of the arm, substantially as herein shown and described, and for the purpose set forth.

GEO. A. GUNTHER.
